UNITED STATES PATENT OFFICE.

LOUIS SCHUTTE, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

VALVE.

1,031,294.

Specification of Letters Patent.

Patented July 2, 1912.

Application filed July 7, 1904. Serial No. 215,639.

To all whom it may concern:

Be it known that I, LOUIS SCHUTTE, a citizen of the United States of America, residing in the city and county of Philadelphia, in the State of Pennsylvania, have invented a certain new and useful Improvement in Valves, of which the following is a true and exact description, reference being had to the accompanying drawings, which 10 form a part thereof.

My invention relates to valve construction, and has for its object to provide a valve which, when closed, will be held to its seat by the pressure of the fluid on its high 15 pressure side and which, at the same time, can be opened with the application of but a small amount of power, and which can be closed by the simple release of a latch.

My improved valve involves the use of a 20 pilot valve and the secondary object of my invention is to provide means for holding the pilot valve in open position when the main valve is also open, thus avoiding variations in pressure in the chamber controlled by the pilot valve with consequent 25 movement or chattering of the main valve.

The nature of my improvements will be best understood as described in connection with the drawings in which—

30 Figure 1, is a sectional elevation of a valve embodying my improvements in what I believe to be their best and most advantageous forms, and Figs. 2, 3 and 4, are elevations, each showing my valve in connection with different devices for actuating the 35 release latch.

A, is the valve casing, A¹ indicating the high pressure and A² the low pressure chambers therein.

40 A³ indicates an opening through the top of the casing into the high pressure chamber, and A⁴ a smaller opening through the bottom of the casing into the low pressure chamber.

45 B is the valve seat through which the chambers A¹ and A² connect.

C is a hollow cylinder secured in the opening A³ as shown, and lying immediately over the valve seat B, the diameter of the 50 chamber in the cylinder being substantially equal to that of the valve which operates in connection with the valve seat B.

D is the cover which is secured over the opening A³ and which is formed, as shown, 55 with a stuffing box D¹ for the valve spindle,

and a guideway D² situated immediately above the same for purposes to be explained. The cover also supports two suitable brackets in which pivot pins D³ and D⁴ are mounted and has formed in it the port D⁵ 60 which leads from the top of the chamber in the cylinder C of the casing, and with the connecting passage C¹ in the wall of the cylinder C, establishes a restricted communication between the chamber in cylinder C 65 and the high pressure chamber A¹.

E indicates a regulating screw by which the effective area of the port D⁵ can be conveniently adjusted.

The main valve F is formed or provided 70 with a piston extension F¹ working in the chamber of cylinder C. The valve is also formed, as shown, with a downwardly extending centrally perforated guide rod F², which is guided in a guideway B¹ secured 75 by radial arms to the valve seat B. The valve, as shown, is formed with a centrally located port F³ F⁴ leading through the piston and valve to the low pressure chamber A², the upper portion F³ of the port being 80 adapted to serve as a seat for the pilot valve. Above this port is situated a small hollow cylinder F⁵, with removable cover F⁶. A port F⁸ leads from the lower end of the chamber in the cylinder F⁵ to the chamber A¹, and a port F⁹ leads from its upper 85 end to the chamber into the cylinder C.

F⁷ indicates a leak port communicating through the walls of the valve with the chamber in the cylinder C. 90

G is the pilot valve adapted to seat itself on the seat F⁸, and having connected with it the piston G¹, G² indicating a gland screwing into the top of the piston G¹, as shown, and serving to hold the valve rod in place. 95 From the bottom of the pilot valve G, and through the perforated spindle F², extends the valve spindle G³, to the lower end of which is attached the plunger piston H, having an area greater than that of the valve rod J, to be described, said plunger

working through the head I, and stuffing box I¹ secured thereto, H¹ indicating a nut by which the plunger piston is held on the valve rod G³. The valve rod J, is formed with a head J¹ which lies below the gland G², and extends up through the stuffing box D¹ and has its upper portion threaded, as indicated at J², J³ indicating a hand wheel for turning the threaded rod. A sliding 110

part K moves in the guideway D² and is here shown as centrally perforated and threaded as indicated at K¹, to receive the threaded portion J² of the valve rod by lugs 5 and a pin. The sliding part K is pivotally connected with the lever L, which is connected with the pivot pin D³ through a link M, and has attached to it at L', the sleeve N, formed with a projecting latch finger N¹, 10 and sliding on a rod O, pivotally connected with the head of the casing at D⁴ and having pivotally attached to its upper end the latch P, which through a rod Q can be connected, see Figs. 2, 3 and 4, with various devices for actuating the latch. Thus in Fig. 15 20 the rod Q is connected with a piston rod R³, the piston R¹ of which, formed with a restricted perforation R², moves in a hollow cylinder R. Into the bottom of the cylinder R leads a pressure pipe R⁴, while from the top of the cylinder leads an outlet pipe R⁵ having in it a valve R⁶. In the construction of Fig. 3, the rod Q is attached to a lever arm S³ pivoted on a bracket S² and moving 25 with a lever arm S⁴ to which is attached electric switch bars S⁵ constituting part of an electric switch S, S¹ indicating the magnet while S⁶ indicates the handle for operating the switch. In the construction of Fig. 30 4, the rod Q is shown as directly attached to and actuated by a ball governor T.

In operation, it will be seen that when the valve F is closed, as shown in Fig. 1, the pressure of the fluid in chamber A¹ will be 35 communicated to the interior of the cylinder C through ports D⁶ and F⁷ and also to some degree through the space between the cylinder C and the piston F¹. It will also be seen that in this position the pressure of chamber 40 A¹ is communicated to the bottom of the chamber in the cylinder F⁶ through port F⁸ and the same pressure is communicated to the top of the chamber through port F⁹. The exposed area of the upper end of the 45 piston G¹ being greater than that of its lower end, the valve G will be held to its seat by the excess pressure. The sliding sleeve K is normally raised, as shown in Fig. 1, and held in its raised position by 50 the engagement of the détent P¹ of the latch P with the lug N¹.

The operator desiring to open the valve F turns the hand wheel J³ in a direction to raise the spindle J. The first effect of this 55 is to lift the pilot valve G from its seat, permitting the escape of the pressure fluid from the chamber in the cylinder C into the low pressure side of the casing, under which condition the valve F and its cylinder F¹ are 60 practically balanced. A further upward movement of the spindle J opens the valve F with but little exertion. It will also be seen that as soon as the pressure is removed from the top of the piston G¹ the high pressure of the compartment A¹ being still main-

tained below the piston, the pilot valve G will be kept away from its seat F⁸ by the resilient cushion between the pilot and main valves provided by the pressure of the fluid in the hollow cylinder F⁶ below the piston G¹, so that any movement of the pilot valve will cause an exactly similar movement of the main valve F. The port F⁸ remains open until the valve F is again seated, whereupon the pressure will accumulate in 70 the cylinder C, and the normal conditions existing when the valve is closed, as already described, will again be resumed. When it is desired to close the valve promptly it is only necessary to disengage the latch P, 80 whereupon the weight of the valve and the parts connected thereto through the rod J will press it downward to its seat; but this action is made more positive and the space occupied by the rod J compensated for by 85 the attachment through the valve rod G³ of the piston H which always insures a downward pull on the valve. The action being first to bring the valve F to its seat, and then to seat the pilot valve G, whereupon 90 the pressure fluid will enter the chamber in the cylinder C through the ports D⁶ F⁷ and the clearance between the cylinder and piston so that the chamber in the cylinder soon acquires the full pressure of the cylinder A¹ 95 which, acting on the piston F¹ holds the valve F to its seat, as of course the pressure in the chamber A² rapidly falls as soon as the valve F is closed.

While of course any means for releasing 100 the latch and permitting the valve to close may be employed, the devices shown in Figs. 2, 3 and 4 are especially well adapted for this purpose, thus, in Fig. 2, the valve R⁶ being closed the pressure fluid coming 105 through conduit R⁴ enters the bottom of the hollow cylinder R and passing through the perforation R² in the piston R¹ fills the cylinder on both sides of the piston with fluid at the same pressure under which condition 110 the piston will remain at the bottom and the latch P in engaging position. As soon as the valve R⁶ is opened, however, the fluid escapes from the upper part of the cylinder R and the passage R² being a restricted one, 115 the pressure in the lower part of the cylinder raises the piston and releases the latch. In the construction of Fig. 3 the latch will remain in engaging position as long as the switch is closed. As soon as the switch is 120 opened the lever S³ is raised and the latch P disengaged. In the construction of Fig. 4, the latch P is directly connected to a ball governor and in such a way as to be disengaged when the speed of the governor rises 125 above a determined point.

It will be observed that the members L and M form a linked connection between the valve casing and the sliding nut K. This connection, when held rigid by the latch P, 130

forms a rigid structure or strut which, in conjunction with the nut and the threaded valve spindle, permits the valve to be opened and closed as desired by the operation of the 5 screw adjustment formed by the nut K and threaded valve stem. When the latch P is tripped this linked connection collapses and the valve closes under the action of the forces then effective to close the valve. 10 These, in the particular form of valve mechanism disclosed, comprise the weight of the valve and of the parts moving with it when the latch is tripped, and also a component due to the pressure of the fluid in the valve 15 casing acting on the enlarged stem portion or piston H. After the valve is closed in this manner and the trip latch P is returned to its normal locking position, the linked connection between the valve and casing 20 may again be locked in its rigid position by returning the sliding nut K to the position shown in Fig. 1. The returning movement of the nut may be brought about by applying a lifting force to the free end of the 25 lever L or through the screw adjustment, by rotating the hand wheel J in the valve closing direction.

Having now described my invention, what I claim as new and desire to secure by Letters Patent is—

1. A valve structure comprising in combination a casing having a valve seat, a main valve adapted to be normally held against said seat by the fluid pressure in the casing, 35 means adapted to equalize the pressure on both sides of said valve, a pilot valve controlling the action of said means, an adjustable part, means supported by said adjustable part for successively opening and closing the pilot and main valves, a latch normally holding said adjustable part in fixed 40 retracted position, and a latch releasing device, said valve structure including provisions for exerting a constantly acting force tending to shift said adjustable part in a direction to close the valves.

2. A valve structure comprising in combination, a casing having a valve seat, a main valve adapted to be normally held against said seat by the fluid pressure in the casing, 50 said valve having a port formed through it, means including a pilot valve controlling the opening and closing of the port in the main valve adapted to equalize the pressure on both sides of the valve, an adjustable part, means supported by said adjustable part for opening and closing the pilot and main valve, a latch normally holding said adjustable part in fixed retracted position, 55 and a latch releasing device, said valve structure including provisions for exerting a constantly acting force tending to shift said adjustable part in a direction to close the valves.

3. A valve structure comprising in combination a valve casing having a valve seated port B, and a hollow cylinder C situated above it, a main valve F with a connected piston F', the latter being movable in cylinder C, said valve having a port formed through it, an adjustable part, means supported by said adjustable part for opening and closing the port in the main valve, a latch normally holding said adjustable part in fixed retracted position, and a latch releasing device, said valve structure including provisions for exerting a constantly acting force tending to shift said adjustable part in a direction to close the valves.

4. A valve structure comprising in combination, a casing having a valve seat, a main valve adapted to be normally held against said seat by fluid pressure in the casing, said valve having a port formed through it, means including a pilot valve controlling the opening and closing of the port in the main valve adapted to equalize the pressure on both sides of the valve, means connecting the main and pilot valves so that the latter may move the former, said means being arranged to permit the pilot valve to move relatively to the main valve to uncover the port in the main valve, an adjustable part, means supported by said adjustable part for successively opening and closing the pilot 75 and main valves, a catch normally holding said adjustable part in fixed retracted position and a latch releasing device, said valve structure including provisions for exerting a constantly acting force tending to move 80 said adjustable part in a direction to close the valves.

5. A valve structure comprising in combination, a casing having a valve seated port and a chamber in line with the port and of 90 a diameter approximately that of the port, a valve adapted to close said port, a piston connected to the valve and adapted to move in said chamber, said valve being formed with a port connecting said chamber with 95 the outlet side of the casing, a pilot valve adapted to open and close said last mentioned port, an adjustable part, means supported thereon for opening and closing the valve, a latch for holding said adjustable 100 part in retracted position, and a latch releasing device for setting said means in operation, said valve structure including provisions for exerting a constantly acting force tending to move said part in a direction to 105 close the valves.

6. A valve structure comprising in combination, a casing having a valve seated port B, and having a hollow cylinder C situated above it, a main valve F with a connected piston F', the latter being movable in cylinder C, a pilot valve arranged to act on a port connecting cylinder C with the exit side of the casing, an adjustable part, means supported thereon for opening and closing 110 the valves, a latch for holding the adjustable part in upper position, said valve structure including provisions for subjecting the main and pilot valves to a constantly acting force tending to close them, and means for releasing said latch to permit said constantly acting force to depress the said adjustable part and close the valves.

7. A valve structure comprising in combination a valve casing having a valve seated 125 port B, and a hollow cylinder C situated above it, a main valve F with a connected piston F', the latter being movable in cylinder C, said valve and piston having a valve seated port connecting the interior of cylinder 130

der C with the outlet side of the casing, a pilot valve arranged to seat on said valve seated port in the main valve, means connecting the pilot valve to the main valve so that when the pilot valve is raised a short distance above its seat it engages and lifts the main valve, a valve rod connected to the pilot valve, a movable part to which the valve rod is adjustably connected so as to open and close the valves when said movable part is stationary, means for latching the movable part in retracted position, and means for releasing said latch, said valve structure including provisions for exerting a constantly acting force tending to draw down the movable part and close the pilot and main valves when said latch is released.

7. A valve structure comprising in combination, a casing having a valve seated port B, and a hollow cylinder C situated above it, a main valve F with a connected piston F', the latter being movable in said cylinder C, said valve and piston having a valve seated port connecting the cylinder C with the outlet side of the casing, a pilot valve arranged to seat on said valve seated port in the main valve, means connecting the pilot and the main valves so that the latter is engaged and lifted when the pilot valve is raised a short distance above its seat, means adapted to provide a resilient cushion tending to hold the pilot valve away from its seat when said valve and the main valve are lifted, a valve rod connected to the pilot valve, a movable part to which the rod is adjustably connected so as to open and close the valves when said movable part is stationary, means for latching the movable part in a retracted position and means for releasing the latch, said valve structure including provisions for exerting a constantly acting force tending to draw down the movable part and close the pilot and main valves when said latch is released.

45 8. A valve structure comprising in combination, a casing having a valve seated port B and hollow cylinder C situated above it, a main valve F with a connected piston F', the latter being movable in said cylinder C, said valve and piston having a valve seated port connecting said cylinder C with the outlet side of the casing, a pilot valve arranged to seat on said valve seated port in the main valve, means connecting the pilot and main valves so that the latter is engaged and lifted when the pilot valve is raised a short distance above its seat, means adapted to provide a resilient cushion tending to hold the pilot valve away from its seat when said valve and the main valve are lifted, a valve rod connected to the pilot valve, a movable part to which the rod is adjustably connected so as to open and close the valves when said movable part is stationary, means for latching the movable

part in retracted position, means for releasing said latch, a hollow cylinder I situated beneath the main valve, and a piston working in said cylinder and connected to the pilot valve, whereby a constantly acting force is applied tending to close the valves when open.

9. A valve structure comprising in combination, a valve seated port B and a hollow cylinder C situated above it, a main valve F with a connected piston F', the latter being movable in said cylinder C, said valve and piston having a valve seated port connecting said cylinder C with the outlet side of the casing, a pilot valve arranged to seat on said valve seated port in the main valve, means connecting the pilot and main valves so that the latter is engaged and lifted when the pilot valve is raised a short distance above its seat, a hollow cylinder F⁵ secured to the main valve and having its interior connected at the upper end to said cylinder C and at the bottom to the high pressure side of the casing, a piston G secured to the pilot valve and working in said cylinder F⁵, said cylinder and piston being adapted to hold the pilot valve away from its seat when the pressure in said chamber falls to that of the low pressure side of the casing, a valve rod connected to the pilot valve, a movable part to which the rod is adjustably connected so as to open and close the valves when said movable part is stationary, means for latching the movable part in retracted position, and means for releasing said latch, said valve structure including provisions for exerting a constantly acting force tending to draw down the movable part and close the pilot and main valves when said latch is released.

10. A valve structure comprising in combination, a casing having a port B connecting its high and low pressure sides and a hollow cylinder situated in line with said port on the high pressure side of the casing, a main valve F arranged to open and close port B, and having a piston F' working in said cylinder C, said piston and valve having a port F³ F⁴ connecting said cylinder C with the low pressure side of the casing, a pilot valve G, arranged to open and close the last mentioned port and when opened to engage and open the main valve, means adapted to provide a resilient cushion between the pilot and main valves when the pilot valve is off its seat tending to hold the pilot valve away from its seat, and means for actuating the pilot valve and through it the main valve.

11. A valve having in combination a casing having a port B connecting its high and low pressure sides and a hollow cylinder C situated in line with said port on the high pressure side of the casing, a main valve F arranged to open and close port B, and

having a piston F' attached to said valve and working in said cylinder, said piston and valve having a port F³ F⁴ connecting said cylinder C with the low pressure side 5 of the casing, a hollow cylinder F⁵ secured to the piston F' and having ports connecting its interior with said chamber and with the high pressure side of the casing, a piston G' working in said cylinder F⁶, a pilot 10 valve secured to said piston G', and means for opening and closing the pilot and main valves.

12. A valve mechanism comprising in combination a valve casing member, a movable valve member and operating means for said valve member comprising coöperating nut and screw elements, one of which is attached to one of said members, a releasable connection between the other element and 20 the other member, and means for releasing said connection, said mechanism including provisions for automatically moving said valve member to the closed position when said connection is released and said valve 25 member being adapted to be opened wholly or partially and closed through said nut and screw when said connection is established and being free to close independently of the nut and screw whenever said connection is 30 released.

13. A valve mechanism, comprising in combination a casing member, a movable valve member and operating means for said valve member including coöperating nut and 35 screw elements one of which is attached to one of said members, a releasable connection between the other element and member, and governor controlled means for releasing said connection, said valve mechanism including 40 provisions for automatically moving said valve member into its closed position when said connection is released and said valve member being adapted to be opened and closed slowly through said nut and screw 45 elements when said connection is established and being free to close independently of the nut and screw elements when said connection is broken, said connection being adapted to be reestablished by the operation of 50 the nut and screw after the valve member has moved into the closed position.

14. A valve mechanism comprising in combination a valve casing, a movable valve, means for holding said valve in adjusted 55 position comprising a screw adjustment and a rigid structure adapted to be collapsed, and means for releasing said structure to permit it to collapse, said valve being adapted to be opened wholly or partially and 60 closed through said nut and screw when said structure is rigid and being free to close independently of said nut and screw whenever said structure is collapsed, and said valve mechanism including provisions for 65 automatically moving said valve to its closed

position when said structure is permitted to collapse.

15. A valve mechanism comprising in combination a valve casing, a movable valve member, means connecting said valve and casing, said means including two elements arranged in tandem, one of said elements being a screw adjustment and the other being collapsible, and an emergency device for bringing about the collapse of said collapsible element, said valve being adapted to be opened wholly or partially and closed through said screw adjustment, when said collapsible element is rigid and being free to close independently of said screw adjustment whenever said collapsible element is collapsed, and said valve mechanism including provisions for automatically moving said valve into its closed position on the collapse of said collapsible element. 70

16. A valve mechanism comprising in combination, a valve casing, a movable valve which is unbalanced and has a tendency to close, an operating stem therefor projecting through the casing and having an external threaded portion, a nut into which said threaded portion is screwed, a linked connection between said casing and nut comprising a pair of elements pivoted together and also pivoted one to the casing and the other to the nut, said elements being adapted to be held rigid with respect to one another to permit the valve to be opened and closed by the operation of said nut and threaded valve stem portion and when released to permit the valve to close without the operation of the nut and threaded stem portion, and means for releasing said link elements. 80

17. In a valve mechanism, the combination with the valve casing, of a movable valve which is unbalanced and has a tendency to close, an operating stem for said valve projecting through the casing wall and having an external threaded portion, a nut into which said threaded portion is screwed, a collapsible linked connection between the nut and casing comprising a pair of members pivotally connected together and also pivotally connected one to said casing and the other to said nut, and means coöperating with said members for releasably holding them against relative movement in position to serve as a strut permitting the operation of the valve by the relative rotation of said nut and threaded stem portion and means for releasing said members to permit the valve to close quickly without said relative rotation. 95

18. A valve mechanism comprising in combination, a valve casing having a valve seated port, a main valve controlling said port and adapted to be held on its seat when closed by the fluid pressure in said casing, means for equalizing the fluid pressure ac- 100 110 115 120 125 130

tion on said main valve including a pilot valve connected, and adapted to have a restricted movement with respect to said main valve, means connected to said pilot valve 5 for holding said main valve in adjusted position, comprising a screw adjustment and a rigid structure adapted to be collapsed, and means for releasing said structure to permit it to collapse, said valve mechanism 10 including provisions for automatically moving said valves to their closed positions when said structure is permitted to collapse.

19. A valve mechanism, comprising in combination, a valve casing, a valve, means 15 for holding said valve in adjusted position, comprising a screw adjustment, a collapsible structure, a trip latch which when in locking position holds said structure in a rigid position, and when tripped permits said structure to collapse, and means for tripping said latch and tending when in normal position to hold said latch in its locking position, said valve mechanism including provisions 20 for automatically moving said valve into its closed position when said structure is permitted to collapse whereby said screw adjustment may be employed to open and close the valve when said structure is held rigid and to relock said structure in its rigid position after its collapse and the return of said latch tripping means to its normal position.

20. The combination with a speed governor of a valve mechanism, comprising a valve casing having a valve seated port, a 35 valve controlling said port, means for holding said valve in adjusted position comprising a screw adjustment and a structure adapted to be held rigid to permit the operation of the valve by said screw adjustment and to collapse to permit the valve to 40 close independently of said screw adjustment, said valve mechanism including provisions for automatically moving said valve to its closed position when said structure is permitted to collapse, and means set in operation by said governor for bringing about the collapse of said structure.

21. A valve mechanism comprising in

combination a valve casing having a valve seated port, a vertically movable valve controlling said port and moving downward to close the latter, balancing provisions whereby the action of the fluid pressure in the casing on the two sides of the valve is substantially balanced when the valve is open, 50 a valve spindle connected to said valve and extending through the casing wall and having an external threaded portion, a nut into which the threaded portion of said stem is screwed, means for locking said nut in an elevated position, means for releasing said nut to permit the valve to close quickly and means supplementing the action of gravity in bringing about the closing movement of the valve when said nut is released. 60

22. In a valve mechanism the combination with a valve casing having a valve seated port, a vertically movable valve member controlling said port and moving downward to close the latter, a vertical valve stem 70 connected to said valve and projecting through the valve casing and having an external threaded portion, a nut into which said threaded stem portion is screwed, guiding provisions for said nut connected to 75 said casing and permitting a vertical sliding movement of the nut, a pivoted latch normally holding said nut in an elevated position, means adapted to supplement the action of gravity in forcing said valve to 80 its seat when said latch is tripped, an emergency device, and operating means between it and the latch through which the latter may be tripped, said operating means tending to hold the latch in its locking position, whereby the nut may be restored to 85 and relatched in its normal position by the rotation of the valve spindle after the latch has been tripped and the connections between the latch and the emergency device 90 have been restored to their normal condition.
